UNITED STATES PATENT OFFICE

WILLIAM ADELBIRT TIFT, OF FRIDAY HARBOR, WASHINGTON.

GAS-ENGINE.

1,082,569.

Specification of Letters Patent. Patented Dec. 30, 1913.

Application filed June 24, 1912. Serial No. 705,647.

To all whom it may concern:

Be it known that I, WILLIAM ADELBIRT TIFT, a citizen of the United States, residing at Friday Harbor, in the county of San Juan and State of Washington, have invented certain new and useful Improvements in Gas-Engines, of which the following is a specification, reference being had therein to the accompanying drawing.

10 This invention relates to gasoline engines and has special reference to a multi-cylinder engine wherein the cylinders revolve around a stationary crank shaft.

15 The principal object of the invention is to provide an improved form of engine of this description having novel means for supplying and exhausting the gases from a plurality of rotating cylinders.

20 Another object of the invention is to provide novel means for controlling the circulation of water through the water jackets of said cylinders.

25 A third object of the invention is to provide a novel timer arrangement and connections therefor, for use with such cylinders.

30 With the above and other objects in view, this invention consists in general of certain novel constructions, combinations and arrangements of parts, as will be hereinafter fully described, illustrated in the accompanying drawings, and specifically claimed.

35 In the accompanying drawings, like characters of reference indicate like parts in the several views, and Figure 1 is a vertical median section through such an engine, the same being shown partly in elevation. Fig. 2 is a detail section on the line 2—2, of Fig. 1. Fig. 3 is a detail partial side elevation, 40 certain of the parts being broken away or shown in section. Fig. 4 is a section on the line 4—4, of Fig. 1, certain of the parts being omitted. Fig. 5 is an enlarged detail view showing the timer mechanism, water 45 pump, and adjacent parts. Fig. 6 is a detail section through a certain member containing exhaust and circulating water passages. Fig. 7 is a detail section showing one of the cams used to operate the timer. 50 Fig. 8 is an end view of the exterior of the timer casing. Fig. 9 is a detail view of certain contacts used in connection with the timer mechanism. Fig. 10 is a detail view showing certain piping connections for the 55 supply pipe for the circulating water system. Fig. 11 is an enlarged detail view of

certain cam mechanism used to control the exhaust valves.

In the present embodiment of the invention there is provided a bed plate 1 from which standards 2 and 3 extend upward arranged in spaced relation on the bed plate. The standard 2 is formed with an opening 4 at its upper end and in this opening is fixed a member 4' constituting a journal for the side frame 5. A second side frame 6 is keyed to the shaft 7 which is rotatably mounted in a bearing 8 formed on the standard 3. The side frames 5 and 6 are secured to the flanges of a cylindrical casing 9 by means of bolts 10 as clearly shown in Fig. 3.

Mounted in the casing 9 is a series of cylinders 11 each of which is provided with a pair of oppositely disposed trunnions 12 and 13 arranged to permit an oscillatory movement of the cylinders with reference to the casing. Leading from each of the trunnions 12 is the L 14 of a pipe 15, this L being provided with a flange through which pass the bolts 16 which secure the pipe to the side frame 5. The other end of the pipe 15 is threaded into the hub of the side frame 5 and communicates with an annular passage 17 extending around the inner periphery of said hub. This passage 17 communicates with a passage 18 which extends outward through what may be termed the hub of the member 4' and the outer end of the passage 18 is threaded as at 19 for the reception of the pipe leading from the carburetor.

Each of the trunnions 13 communicates with one end 20 of an S-shaped pipe 21 which is secured to the casing 9 in the same manner that the pipe 14 is secured. The other end 22 of the pipe 21 is connected with one end 23 of an S-shaped pipe 24 by means of bolts 25 which pass through flanges 26 formed on the adjacent ends of the pipes 21 and 24, respectively. The remaining end 27 of each pipe 24 is connected with a passage 28 by means of bolts 29 passing through flanges 30, formed in a member 30' which is fixed upon the shaft 7. This passage 28 communicates with an exhaust pipe 31 by means of an annular groove 32 formed on the inner side of the casing 33 which is provided with suitable packing glands 34 and 35 and is secured to the standard 3 fixedly by means of the bolts 36.

Each of the cylinders 11 is provided with

a piston 37, each of which is connected by a neck 37' to a segmento-cylindrical bearing 38 which engages a crank 39 formed on the member 4'. This crank is eccentric to the 5 casing 9 and consequently if the latter be rotated the pistons will be alternately forced in and drawn out. Conversely, if the pistons are forced in and drawn out, they, with the casing 9, will be caused to rotate. The bearings 38 are held in position by collars 40. At the end of the crank 39 opposite the member 4' there is provided a crank arm 42 having a bearing opening 43 therein and in this bearing opening fits the end of the 15 shaft 7, the opening and bearing being concentric with the casing 9. The shaft 7 is keyed to the hub 44 of the side frame so that as the casing revolves so also will the shaft revolve.

20 Within each of the trunnions 12 is mounted an intake valve 45 which is provided with a spring 46 and has its stem slidably mounted in a bearing 47 held in position by spaced brackets 48 secured to the inner walls of the 25 trunnion. Within each of the trunnions 13 is an exhaust valve 49 similar to the valve 45 but provided with a ball and socket connection 50 which joins the stem of the valve proper with a stem 51 which projects 30 outward from the pipe 21 and has mounted on its outer end a spring 52 and collar 52' to hold the valve in closed position.

Secured to each of the pipes 21 is a bracket 53 upon which is pivotally mounted the central part of a bell crank lever provided with the arms 54 and 55. The arm 54 bears against the end of the stem 52 while the arm 55 is provided with a suitable opening for the reception of the end of a rod 56, the arm 40 being adjusted with respect to the rod by means of a nut 57 held upon the threaded portion of said rod. The lower end of the rod 56 is bifurcated and each of the bifurcations is again bifurcated to provide the 45 fingers 58. These fingers 58 straddle a shaft 59 and between the first bifurcations is revolvably mounted a roller 60 and on the shaft 59 is a cam 61 which engages with the roller. The shaft 59 for each rod 56 is 50 mounted in a bearing 62 formed on the side member 6. Mounted upon the shaft 59 is a gear 63 which meshes with a gear 64 actuated upon the member 43 so that the gear 64 is prevented from rotating.

55 The outer end of each of the pipes 24 has adjacent thereto a valve seat which is formed in the pipe 21 and on this seat is adapted to fit a valve 65 which is held in position by a suitable spring 66.

60 In order to supply water to the water jackets 67 of the respective cylinders there is provided within the casing an annular pipe 68 which communicates with the respective jackets 67 through branch pipes 69 65 which are partially constructed of flexible

material such as rubber hose. Connected with this pipe 68 is a pipe 70 which communicates with an annular passage 71 formed in the member 30', this passage in turn communicating with a supply pipe 72 70 by means of an annular groove 73 formed in the member 33. The pipe 72 communicates with a circulating pump 74 held on a bracket 75 held to the standard 3 by the same bolts 36 which hold the member 33 to said standard. This pump is provided with suitable inlet and outlet valves not deemed necessary here to be shown. Actuating the piston of the pump 74 is an eccentric 76 which is fixed upon a shaft 77 revolvably mounted in a bearing 78 formed on the member 75. The overflow from the water jackets of the cylinders is carried through pipes 79 which connect to one of the cylinders partially constructed of rubber hose, and each of these pipes 79 is connected to the water jacket 80 of a respective pipe 21. From each of these water jackets 80 it passes through a passage 81 and communicates with the respective pipe 24.

90 In order to effect the ignition of the gases I prefer to do so by means of the jump spark system. In carrying out this part of the invention there is provided a gear wheel 82 which is fixed upon the shaft 7 and meshes with a gear wheel 83 fixed upon the shaft 77. There is also fixed upon the shaft 77 a gear wheel 84 which meshes with a gear wheel 85 provided with an elongated hub. On the hub of the gear wheel 85 is a series 95 of cams 86, equal in number to the number of the cylinders 11 and inclosed by a housing or casing 87 which is supported by an arm 88 provided with a bearing 89 journaled on the bearing 8 of the standard 3. Located in the plane of the path of the respective cams is a series of insulated binding posts 90 to which the wires forming the high tension circuit are connected. Pivottally connected to the casing 87 are 100 also a series of levers 91 equal in number to the number of cams and each bearing upon a respective cam 86 being pressed thereon by the springs 92. Each of the springs 92 carries at one end a contact point 93 and these contact points are arranged to contact with the inner ends of the respective posts 90.

110 Projecting from the arm 88 is an arm 94 which is provided with spaced bearings in 120 which is slidably mounted an insulated rod 96, the insulation being surrounded by metal tube 97 which is threaded for a portion of its length. On the threaded portion of the tube there is provided a nut 98 and between this nut and one of the bearings 95 is a spring 99 which normally urges the rod in the direction of the cylinders 11.

125 Extending through the arm 88 and the bearing 89 is a threaded set screw 100 which 130

is used to move the arm 88 around the shaft 7 and thus vary the position of the rod 96 whereby the spark may be advanced or retarded.

5 Secured to the member 30' is a series of brackets 101, each provided on its outer end with a bearing wherethrough passes a binding post 102, the same being held in position by means of the nuts 103. As the engine revolves the binding posts 102 will be carried around and contact successively with the posts 96, the spring yielding to prevent injury during contact.

10 Mounted in a threaded socket in each of the cylinders 11 is a spark plug 104. Each of the spark plugs is connected to a respective binding post 102 by suitable wiring not deemed necessary here to be shown as the same is obvious.

20 On the journal member 4' is mounted a pair of annular angle irons 105 which are pressed against the hub 5 by means of the springs 106.

Attached to the casing 9 by means of bolts 25 108 is a plate 107, the bolts passing through suitable flanges 109. The plate thus forms a portion of one of the flanges in the casing 9 but at the same time by its removal permits the removal of the cylinders.

30 The operation of the engine is as follows: In order to start the engine the casing 9 is rotated by any suitable means and the pistons 37 are moved in and out of the respective cylinders, as previously described. This causes a suction within the respective cylinders, the said suction taking place successively in the series. Further rotation of the casing 9 causes compression of the drawn in gases and when 40 the cam 86 for one of the cylinders is in proper position and the respective post 102 engages the post 94 a spark will cross the spark gap of the plug and an explosion will take place. This causes the rotation of the casing and cylinders therewith as previously described. The cylinders will thus be successively fired and upon further rotation will be on the exhaust stroke. Now, as the gear 63 is carried around the fixed gear 64 and cam 61 will be operated for the respective cylinder to which it belongs. Thereupon at the proper time the rod 56 will be raised and the valve 49 opened, thus permitting the exhausted gases to pass out 50 through the pipe 21 and its connections into the grooves 32 from whence they will pass through the exhaust 31.

It is to be noted that by means of the valves 65 any water which may overflow 60 from the water jackets 80 of the respective cylinders will be prevented from flowing backward into the cylinder itself because it will be carried out with the exhausted gases during the exhaust stroke.

65 There has thus been provided a simple

and efficient device of the kind described, and for the purpose specified.

It is obvious that many minor changes may be made in the form and construction of the invention without departing from the material principles thereof, and it is therefore not wished to confine the invention to the exact form herein shown and described, but it is wished to include all such as properly come within the scope claimed.

Having thus described the invention, what is claimed as new, is:—

1. In a gas engine, a standard, a journal member fixed in said standard, a crank projecting eccentrically from said journal member, a bearing at the opposite end of said crank, a casing revolubly mounted on said journal member, a second standard having a bearing in alinement with the first-mentioned bearing, a shaft carried in said bearings and fixed to said revoluble casing, a plurality of cylinders mounted for oscillatory movement in said casing, a water jacket for each cylinder, a pipe extending in a circle within said casing, a flexible connection between each water jacket and said pipe, exhaust pipes leading from said cylinders, and a flexible connection between each exhaust pipe and the water jacket of the respective cylinder.

2. In a gas engine, a standard, a journal member fixed in said standard, a crank projecting eccentrically from said journal member, a bearing at the opposite end of said crank, a casing revolubly mounted on said journal member, a second standard having a bearing in alinement with the first-mentioned bearing, a shaft carried in said bearings and fixed to said revoluble casing, a plurality of cylinders mounted for oscillatory movement in said casing, a water jacket for each cylinder, a pipe extending in a circle within said casing, a flexible connection between each water jacket and said pipe, exhaust pipes leading from said cylinders, a flexible connection between each exhaust pipe and the water jacket of the respective cylinder, and means to supply water to said circular pipe while the casing is revolving.

3. In a gas engine, a standard, a journal member fixed in said standard, a crank projecting eccentrically from said journal member, a bearing at the opposite end of said crank, a casing revolubly mounted on said journal member, a second standard having a bearing in alinement with the first-mentioned bearing, a shaft carried in said bearings and fixed to said revoluble casing, a plurality of cylinders mounted for oscillatory movement in said casing, a water jacket for each cylinder, a pipe extending in a circle within said casing, a flexible connection between each water jacket and said pipe, exhaust pipes leading from said cyl-

inders, a flexible connection between each exhaust pipe and the water jacket of the respective cylinder, and means to supply water to said circular pipe while the casing is revolving, said means comprising a stationary member of hollow cylindrical form provided with an internal annular groove, a cylindrical member fixed on said shaft and provided with a passage having port communication with said groove, and a pipe connecting said passage with said circular pipe.

4. In a gas engine, a standard, a journal member fixed in said standard, a crank projecting eccentrically from said journal member, a bearing at the opposite end of said crank, a casing revolvably mounted on said journal member, a second standard having a bearing in alinement with the first-mentioned bearing, a shaft carried in said bearings and fixed to said revolvble casing, a plurality of cylinders mounted for oscillatory movement in said casing, a water jacket for each cylinder, a pipe extending in a circle within said casing, a flexible connection between each water jacket and said pipe, exhaust pipes leading from said cylinder, a flexible connection between each exhaust pipe and the water jacket of the respective cylinder, and means to supply water to said circular pipe while the casing is revolving, said means comprising a stationary member of hollow cylindrical form provided with an internal annular groove, a cylindrical member fixed on said shaft and provided with a passage having port communication with said groove, and a pipe connecting said passage with said circular pipe, a pump for supplying water to said annular groove, and means for operating said pump.

40 5. In a gas engine, a standard, a journal member fixed in said standard, a crank projecting eccentrically from said journal member, a bearing at the opposite end of said crank, a casing revolvably mounted on said journal member, a second standard having a bearing in alinement with the first-mentioned bearing, a shaft carried in said bearings and fixed to said revolvble casing, a plurality of cylinders mounted for oscillatory movement in said casing, a water jacket for each cylinder, a pipe extending in a cir-

cle within said casing, a flexible connection between each water jacket and said pipe, exhaust pipes leading from said cylinder, a flexible connection between each exhaust 55 pipe and the water jacket of the respective cylinder, means to supply water to said circular pipe while the casing is revolving, said means comprising a stationary member of hollow cylindrical form provided with an 60 internal annular groove, a cylindrical member fixed on said shaft and provided with a passage having port communication with said groove, and a pipe connecting said passage with said circular pipe, a pump for 65 supplying water to said annular groove, and means for operating said pump, said means comprising a beveled gear fixed on said shaft, a bracket extending from said second standard, a shaft journaled in said bracket, 70 a beveled gear carried by said shaft and meshing with the first mentioned beveled gear, an eccentric mounted on said shaft, a piston in said pump, and a piston rod fixed to said piston and provided with an eccentric 75 strap surrounding said eccentric.

6. In a gas engine, a standard, a journal member fixed in said standard, a crank projecting eccentrically from said journal member, a revoluble casing mounted on said journal member, a plurality of cylinders mounted for oscillatory movement in said casing, pistons in said cylinders connected to said crank, a plurality of exhaust pipes carried by said casing and revolving therewith, a water jacket for each cylinder, a water jacket for the portion of each exhaust pipe adjacent the respective cylinder, a valve in each exhaust pipe, a flexible connection between the water jacket of each cylinder and the water jacket of its respective exhaust pipe, a connection between the water jacket of the exhaust pipe and the exhaust pipe proper, said connection opening into the exhaust pipe beyond said valve. 95

In testimony whereof I hereunto affix my signature in presence of two witnesses.
